S. DUFRENE

GAME TRAP

Filed March 18, 1925

Patented Feb. 9, 1926.

1,572,384

UNITED STATES PATENT OFFICE.

SYLVESTER DUFRENE, OF LOCKPORT, LOUISIANA, ASSIGNOR OF ONE-HALF TO C. A. BUCHLER, OF WESTWEGO, LOUISIANA.

GAME TRAP.

Application filed March 18, 1925. Serial No. 16,454.

To all whom it may concern:

Be it known that I, SYLVESTER DUFRENE, a citizen of the United States, residing at Lockport, in the parish of La Fourche and 5 State of Louisiana, have invented certain new and useful Improvements in a Game Trap, of which the following is a specification.

The present invention relates to a trap 10 particularly designed for game of the fur bearing character, and has for its principal object to provide a trap of this nature which may be easily set without danger to the person setting the same and will prove efficient and reliable in operation.

Another important object of the invention is to provide a trap of this nature which is simple in construction, one which may be manufactured at a comparatively low cost 20 and yet be strong, durable, and well adapted to the purpose for which it is designed.

With the above and numerous other objects in view as will appear as the description proceeds, the invention resides in certain novel features of construction, and in the combination and arrangement of parts 25 as will be hereinafter more fully described and claimed.

In the drawing:—

30 Figure 1 is a top plan view of the trap in a set position,

Figure 2 is a side elevation thereof in its sprung position.

35 Figure 3 is a perspective view of the closing plate, and

Figure 4 is a detail perspective view of the auxiliary catch or trigger.

Referring to the drawing in detail, it will be seen that 1 designates a base which in the 40 present instance is provided with the four upstanding spaced lugs 2. A pair of outer jaws 3 are pivoted to the outer lugs 2 and a pair of inner jaws 4 are pivoted to the inner lugs 2. These jaws 3 and 4 are of a general U-shaped formation having offset pintle ends 5 which pierce the respective lugs 2. One end of the base 1 is curved over upon itself so as to form a loop 6 for receiving a link 7 to which an anchoring chain or other suitable means may be attached.

45 A U-shaped plate 9 includes an intermediate upper portion 10 and depending side portions 11. The intermediate upper portion 10 has a pair of circular openings 12 therein for receiving two of the adjacent

5 lugs 2 while the sides 11 are provided with elongated slots 13. A spring of the helical type indicated at 14 has its lower end disposed over a member 15 rising from the base 1 and its upper end disposed over a similar 60 member, indicated in dotted lines in Figure 2, on the bottom of the intermediate portion 10 of the plate 9, and normally holds the plate raised so as to close the jaws 3 and 4 as is indicated to advantage in Figure 2. 65

70 Triggers or catches are provided for normally holding the plate down when the trap is set in order that the jaws may be open as in Figure 1. One of these triggers is indicated generally by the letter A and is of an integral formation including a catch proper 17, a pair of parallel spaced arms 18 terminating in outwardly disposed L-shaped lugs 19 and a pair of sleeves 20 in registry 75 with each other and spaced from each other. These sleeves 20 receive pin 21 which is held on the end of the base by a bent over portion 22. The lugs 19 are receivable in the slots 13. The other trigger is indicated generally by the letter B and includes a plate 23 on which may be placed suitable bait. This plate 23 is supported on a bar 24 pivoted on the upper end of an upright 80 25 disposed on the intermediate portion of the base 1. The bar 24 has a catch 26. The 85 catches 17 and 26 are adapted to engage the ends of the plate 9 so as to hold it down so that the lugs 2 project through the openings 12 thereof at which time the jaws 3 and 4 may be disposed horizontally or open. If 90 the animal disturbs the trigger B the spring 14 will raise the plate 10 thereby causing the closing of the inner and outer pairs of jaws 3, 4.

95 By holding the two pairs of jaws in an upright position a person may bear down on the plate 9 with his foot, and the catch 17 of the trigger A will automatically engage over the adjacent end of the plate, and the other trigger B may be set with its catch 100 26 over the adjacent end of the plate 9 for holding this plate down. When the plate 9 is down the person may then release the jaws 3 and 4 and they will swing down to the horizontal set position so that as soon as an animal disturbs the trigger B he will be caught in the trap.

105 It is thought that the construction, operation, and advantages of this invention will now be clearly understood by those 110

skilled in this art without a more detailed description thereof. It is apparent that the present embodiment of the invention which I have described in detail has been disclosed merely by way of example and that numerous changes in the details of construction, in the sizes, and in the combination and arrangement of parts may be resorted to without departing from the spirit or scope 10 of the invention as hereinafter claimed or sacrificing any of its advantages.

Having thus described my invention, what I claim as new is:—

1. A trap of the class described including 15 a base, a pair of lugs rising from the base, a pair of U-shaped jaws having their ends pivoted to the lugs, a plate of U-shaped formation including an intermediate portion having an opening and sides having 20 slots, a trigger including a catch for engaging one end of the plate, means for pivoting the trigger to the base, arms extending from the trigger and terminating in extensions disposed in the slots of the plate, a second 25 trigger including a catch for engaging the

other end of the plate, means for pivoting the second trigger on the base, a bait plate on the second trigger, one of the lugs being receivable in the opening of the plate so that when the plate is released from the triggers, 30 it will be raised by the spring so that the opening will engage the jaws for closing said jaws.

2. A trap of the class described including 35 a base, a pair of lugs rising from the base, a pair of U-shaped jaws having their ends pivoted to the lugs, a plate having depending sides, said plate provided with an opening 40 for receiving one of the lugs and sides of the jaws pivoted thereto, a spring normally urging said plate upwardly for closing the jaws, a bait trigger engageable with one end of the plate for holding it in a lowered position, an auxiliary trigger operatively connected with the plate so as to engage the 45 other end of the plate when the plate is in a lowered position.

In testimony whereof I affix my signature.

SYLVESTER DUFRENE.
